FIG. 1

FIG. 2

FIG. 1 is a top plan view of a luggage case or similar article embodying my new design; and

FIG. 2 is a perspective view of the luggage case or similar article embodying my new design.

The essential feature of my design resides in the portion shown in full lines and more specifically in a luggage case or similar article having lines on the valance, handle studs and lock or locks which lines extend parallel to one another.

I claim:

The ornamental design for a luggage case or similar article, as shown and described.
